UNITED STATES PATENT OFFICE.

OSCAR F. BOOMER, OF BROOKLYN, NEW YORK, ASSIGNOR ONE-THIRD TO
CHAS. G. TILL, OF SAME PLACE.

APPARATUS FOR REMOVING SNOW AND ICE FROM STREETS.

SPECIFICATION forming part of Letters Patent No. 244,536, dated July 19, 1881.

Application filed March 7, 1881. (No model.)

To all whom it may concern:

Be it known that I, OSCAR F. BOOMER, of Brooklyn, Kings county, New York, have invented a new and Improved Apparatus for Removing Snow and Ice from Streets, of which the following is a specification.

The object of this invention is to remove snow and ice from streets in a most speedy and inexpensive manner.

10 The invention consists in laying steam-pipes along the street-gutters for receiving the exhaust-steam from the boilers that are used for heating or mechanical purposes in the buildings bordering on the streets, or for receiving steam from other sources especially arranged for that purpose; and it consists, further, in constructing suitable water seals or traps to the pipes in the sewer-inlets to prevent the escape of steam, and in constructing or applying a 15 suitable bed for supporting said steam-pipes, so that they shall better withstand the shocks and wear of heavy vehicles, the intention being to have steam always in these pipes in cold weather, to melt the snow and ice that may be thrown into the gutters upon said pipes from 20 sidewalks or roadways.

Figure 1 is a perspective view, showing the apparatus in position in a street. Fig. 2 is a 25 sectional elevation of the same on line xx , Fig. 1, and Fig. 3 is a sectional elevation of the water-trap and connection.

In the drawings, A represents the roadway, B the sidewalks, C the gutters, and D a sewer-inlet.

30 E represents an iron plate provided with a longitudinal channel or depression, a , laid in a gutter, C, for receiving and supporting the steam-pipe F that is placed in the channel a . These channels a in the plate E are designed to be of sufficient depth to permit the pipes F to lie in them for half or more of the diameter of said pipes, so that said pipes F may be well 35 protected from displacement or injury from the wheels of passing vehicles. These plates E, when used, are designed to be extended the

whole length of the gutter beneath the pipe F; but said plates E may in some instances be dispensed with and the pipes F be laid in suitable channels formed in the gutter-pavement.

Connected with the ends of the pipes F in 50 the sewer-inlet D is shown a water-trap, G, into which flows the water from the steam condensing in the pipes F, as shown at b , which water forms a seal that prevents the escape of steam from said pipes F. An overflow, c , from 55 the trap G carries off the water to the sewer as it accumulates.

A valve, H, in the bottom of the trap G, operated by means of a rod, d , that extends upward within easy reach of the operator, may 60 be opened to permit the escape of all the water in the trap G, to prevent its freezing at any time, or in order to permit a free escape for the steam in the pipes F.

In a street supplied with this apparatus in 65 operating condition the snow and ice, if thrown from roadway and sidewalks into the gutter, which can be done at comparatively little expense, will be rapidly melted and run off into the sewers.

The device is inexpensive and puts to the best use the exhaust-steam that is always escaping in winter from offices, factories, dwelling-houses, and other buildings in a city.

Having thus described my invention, I claim 75 as new and desire to secure by Letters Patent—

1. As a means for removing snow and ice from the gutter, steam-pipes F, provided with water-traps G, arranged and operated substantially as herein set forth.

2. In an apparatus for removing snow and ice from streets, the combination, with the steam-pipes F, of the plates E, provided with channels a , substantially as herein shown and described, said plates serving to support and 85 protect the pipes, as set forth.

OSCAR F. BOOMER.
